I claim the ornamental design for an inspection device for medical tablet, as shown and described.

DESCRIPTION

FIG. 1 is a front perspective view of an inspection device for medical tablet of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The dash-dot lines immediately adjacent the shaded areas represent the bounds of the claimed design while other broken lines are included for the purpose of illustrating the unclaimed portions of the inspection device for medical tablet. None of the broken lines form part of the claimed design.
